ELECTRIC LAMP SOCKET

George Henry Elwell, New Haven, Conn., assignor to The Greist Manufacturing Company, a corporation of Connecticut

Application August 17, 1927. Serial No. 213,671

4 Claims. (Cl. 173—355)

The invention relates to improvements in electric lamp sockets and especially in that type of sockets employing a one-piece shell with an integral or permanently assembled cap. In the manufacture of a two-part socket, comprising the usual cap and shell, it is customary to form-up the shell from flat stock and, as that type of a shell has a forwardly facing lamp receiving end of a reduced diameter, that reduced end during the forming-up process and before completion is capped over. This cap is afterwards cut off to provide an orifice at the previously capped end for the reception of the lamp and, for the end having the greater diameter, a separable cap is provided which requires a finely calculated means for the uniting of the cap and shell against axial and rotary movements. The manufacture of sockets by a process producing a shell with an integral cap which must be discarded and then requiring the making of another cap for a separable connection to the shell by an expensive means with which both cap and shell are provided is a thing to be avoided in seeking a form of socket casing of minimum cost. The development of the art discloses previous attempts to produce a unitary or one-piece socket casing, but the difficulty apparently lies in an endeavor to devise a suitable means for locking the contents within the one-piece socket casing of equal diameter throughout its axial formation, and at the same time to establish a practical manner in which the manual switch operative means may be separably connected with the switch element through transverse openings in the cylindrical wall of the socket casing and lining. It is therefore the object of this invention to provide a socket casing of the one-piece type to reduce the manufacturing cost of lamp sockets to a minimum; to provide a convenient and effectual means for locking within the casing the usual socket contents; and to provide a practical and adequate means for connecting separable manual operative means to the switch element within the casing.

With these and other objects in view, as will more fully hereinafter appear, the invention consists in certain features of novel construction and arrangement of parts hereinafter described, illustrated in the accompanying drawing and pointed out wherein patentable novelty is claimed for certain features of the device, it being understood that within the scope of what hereinafter thus is claimed various changes in form, proportion, size, and minor details of the construction, can be made without departing from the spirit

or modifying any of the advantages of the invention.

The following is the description of an embodiment of the invention, reference being had to the accompanying drawing (one sheet) in which Figure 1 is an upright elevation in cross-section of the one-piece socket casing with the contents in the progress of being assembled therein and the switch operative means being in position for final connection with the switch element; Figure 2 is a similar elevation but with parts fully assembled; the Figure 3 is a detail view of an insulation body portion; and the Figure 4 is a detail view of an insulation sleeve portion.

Referring more particularly to the drawing, in which similar parts are similarly numbered, the socket casing 1 is preferably illustrated as a one-piece construction as involving the minimum manufacturing cost although the casing might be made of two or more pieces permanently assembled so far as the applicability thereto of the novel features hereinafter disclosed may be concerned. In addition to the usual nipple aperture 2 in the capped end of the casing, and the lamp-receiving opening 3 at its forwardly facing end, the cylindrical wall of the casing is provided with such necessary transverse opening, as at 4, as the radial insertion from the exterior and support of the switch operative means shall require. The casing is further provided with a rolled or formed-in screw-thread 5 in the thin metal and around its forwardly facing end, the purpose of which in connection with the novel features introduced by this invention will be hereinafter explained. The body of insulation 6 in assembled position is made to rest against the interior curved surface of the capped end of the socket casing and is provided with an annular shoulder 7 facing forwardly and having in its face one or more recesses, as at 8, for a purpose to be later explained. The insulation lining 9 is made in the customary cylindrical form to lie more or less snugly within the interior of the casing and to bear against the annular shoulder 7, the rearwardly extending lugs 10 provided by the lining engaging within the recesses 8 to maintain a certain relative rotary position of both lining and body within the socket casing. The thickness of the wall of the lining at its free end is reduced to exteriorly provide the annular shoulder 11 also forwardly facing, the purpose of which will be later explained. The body of insulation carries the screw-shell and center contacts 12 and 13, respectively, and also a reciprocating switch element not specifically illustrated

- but generally represented, as at 14, to disclose the rearwardly directed extremities 15 which must be carried by whatever reciprocating switch element is employed in connection with the novel features herein disclosed, each of the extremities having a transverse perforation, as at 16, for a purpose to be later explained. In addition to the necessary cavity or runway, as at 17, with which the body of insulation is provided for the accommodation and movement of the reciprocating switch element, a sufficient enlargement of the cavity extremities, as at 18, must be provided for the radial insertion of the push elements 19 when the parts in the progress of assembly are in the position illustrated by Figure 1. The insulation lining is provided with the transverse opening 20 to register with the enlargement 18. Each of the push elements is made of the customary insulation material and is provided rigidly mounted at its inner end with a metal clasp 21 with an extremity of slight resiliency provided with a bur 22 facing the inner end of the push element. A sheet metal locking collar 23, adapted to be inserted into the forward end of the socket between the socket casing and the insulation lining, is provided with a rolled or formed-in screw-thread 24 adapted to mesh with the internal presentation of the casing screw-thread 5, the locking collar being provided with an inner annular edge 25 adapted to bear against the annular shoulder 11 of the insulation lining. The locking collar is also provided with an outer rolled edge 26 extending forwardly beyond the socket casing and which may be knurled to provide a roughened surface for manual rotation.
- In assembling the parts of the electric lamp socket they are placed in the relative order and position illustrated by Figure 1, and then further inserted within the socket casing and the locking collar rotated until the parts of insulation are sufficiently held in place thereby. While the insulation parts are being finally positioned the push elements are held in the position illustrated by Figure 1 in readiness to engage their clasps 21 over and about the extremities 15 of the switch element, the burs 22 snapping into their respective perforations 16, the engagement between bur and perforation co-operating with the clasp connection in maintaining the correct position of the push element while locked against withdrawal by means of the locking collar holding the insulation parts against axial movement.
- No attempt is herein made to illustrate or describe the electric switch element in specific form or the location of the binding posts and wire connections as none has any direct relative importance to the matter of disclosure of the novel features herein set forth.
- What I claim is:—
1. An electric lamp socket comprising, in part, a casing having through its opposite wall portions a transverse opening; a body of insulation having a forwardly facing shoulder and carrying a reciprocating switch element having rearwardly directed extremities; an insulation lining having through its opposite wall portions a transverse opening and also having a forwardly facing shoulder, the rear end of the lining bearing against the body shoulder; locking means provided by the forward end of the casing and adapted to bear rearwardly against the lining shoulder; and manual switch operative means comprising push elements having at their inner ends forwardly facing open slots, each adapted to receive one of the rearwardly directed extremities of the

switch element as the push elements are radially inserted within the transverse openings and held in the path of the rearwardly borne body of insulation upon the assembly of the insulation parts within the casing, the manual means being maintained in locked relation to the switch element by the means locking the insulation parts within the casing against relative axial movement.

2. An electric lamp socket comprising, in part, a casing having through its opposite wall portions a transverse opening; a body of insulation carrying a reciprocating switch element having rearwardly directed extremities; an insulation lining having in its opposite wall portions a transverse opening therethrough; a locking means provided by the casing and insulation parts to lock the parts within the casing against forward axial movement; and manual switch operative means comprising push elements having at their inner ends forwardly facing open slots, each adapted to receive one of the rearwardly directed extremities of the switch element as the push elements are radially inserted within the transverse openings and held in the path of the rearwardly borne body of insulation upon the assembly of the insulation parts within the casing, the manual means being maintained in locked relation to the switch element by the means locking the insulation parts within the casing against relative axial movement.

3. An electric lamp socket comprising, in part, a casing having in its opposite wall portions a transverse opening therethrough and a screw-thread rolled in the metal around its forward end; a body of insulation having a forwardly facing annular shoulder with spaced recesses in the face thereof, the body carrying a reciprocating switch element having rearwardly directed extremities, each having a perforation; a cylindrical insulation lining having in its opposite wall portions a transverse opening therethrough and also having a forwardly facing annular shoulder and rearwardly extending spaced lugs to engage with in the recesses as the lining bears against the body shoulder; manual switch operative means comprising push elements provided at their inner ends with clasps, each having a resilient extremity provided with a bur, each clasp being adapted to receive one of the switch extremities as the push elements are radially inserted within the transverse openings and held lying in the path of the rearwardly borne switch extremities for clasping engagement therewith upon the assembly of the insulation within the casing, the bur of each clasp snapping into the perforation of its respective switch extremity; and a locking collar having an external screw-thread for engagement with the casing screw-thread, a rearwardly extending annular edge of the collar engaging the lining shoulder and an annular portion of the collar extending forwardly beyond the casing to provide means for the manual rotation of the collar to lock the insulation parts within the casing against axial forward movement and thereby maintain the push elements in locked relation with the switch element.

4. An electric lamp socket comprising, in part, a cylindrical casing having a capped end and a forwardly facing open end; a transverse opening through the casing; a body of insulation insertable through the open end of the casing and having a peripherally reduced portion providing the body with a forwardly facing annular shoulder; a recess in the face of the annular shoulder; a transverse cavity extending through the reduced

portion, the body carrying within the cavity a reciprocating switch element having rearwardly directed extremities of which each is provided with a perforation; an insulation casing-lining 5 surrounding the reduced portion of the body and having a peripherally reduced portion providing the lining with a forwardly facing annular shoulder, an end of the lining being engageable with the body shoulder and being provided with a lug 10 engageable within the recess; a transverse opening through the lining; manual switch operative means comprising push elements provided at their inner ends with clasps, each having a resilient ex-

tremity provided with a bur, each clasp being adapted to receive one of the switch extremities as the push elements, radially inserted within the transverse openings, are held in the path of the rearwardly borne switch extremities for clasping engagement therewith upon the assembly of the body and lining of insulation within the casing, the bur of each clasp snapping into the perforation of its respective switch extremity; and locking means provided by the open end of the casing and engageable with the lining shoulder.
